STEADYING DEVICE FOR LADDERS

Isabelle J. Backlin and Carl A. Backlin,
Burlington, Wis.

Application February 26, 1945, Serial No. 579,786

2 Claims. (Cl. 228—67)

1

The invention relates to ladders and more particularly to an attachment for ladders.

The main object of the invention is to provide a handle readily attachable to ladders, more particularly those of the stepladder type which will help to steady a user of the ladder when going up or down and when standing on the top thereof.

A further object of the invention is to provide a steady handle attachment for ladders that may be folded back adjacent a ladder leg when not in use and may be locked in operative position when in use.

The invention further consists in the several features hereinafter set forth and more particularly defined by claims at the conclusion hereof.

In the drawings:

Fig. 1 is a side elevation view of a ladder equipped with the device embodying the invention;

Fig. 2 is a front elevation view of the device in operating position on a ladder;

Fig. 3 is a detailed sectional view taken on the line 3—3 of Fig. 1;

Fig. 4 is a detailed sectional view taken on the line 4—4 of Fig. 1 with the handle in folded position;

Fig. 5 is a detailed side elevation view of parts of the structure showing it in folded down condition;

Fig. 6 is a front elevation view of the parts shown in Fig. 5.

Referring to the drawings, the numeral 7 designates a ladder, here shown as a stepladder having the usual ladder portion 8, top 9, and brace legs 10 pivoted at 11 and held in operating position by the usual foldable brace bars 12.

The steadyng handle attachment embodying the invention includes an attaching plate 13, a steadyng member or handle 14 pivotally mounted on a pin 15 carried by said plate, means for locking said handle in operative position, and a metal clip 16 for securing said handle in a folded or inoperative position.

The attaching plate 13 is preferably formed of sheet metal adapted to rest against the side of one of the legs 10 and be there secured by screws 17 and a flange 18 adapted to abut the front of said leg to aid in positioning said plate and to relieve the screws 17 of shearing strains.

The handle 14 is preferably a rectangular stick of wood and in its operating position is disposed at a point above its pivot between the plate 13 and a metal clip 19 riveted to said plate, and when so positioned, is locked against movement by a latch 20 pivoted on a pin 21 carried by a flange 22 on the plate 13 and adapted to be swung down to bring its free end into a notch 23 in said clip 19 as shown in Figs. 1 to 3 or be

2

swung up to a release position as shown in Figs. 5 and 6. When the latch 20 is released, the handle 14 may be swung down to bring its free end in registry with the spring clip 16 to hold it between the free end of this clip and the side of the leg 10 of the ladder as shown in Fig. 4.

When in upright position the handle may be grasped by one hand of the person in going up or down the ladder and is of great help in steadyng said person, or in some conditions of use where a person works from the top 9 of the ladder, the steadyng action of the handle enables him to reach out a considerable distance from the ladder without danger of losing his balance.

15 We desire it to be understood that this invention is not to be limited to any particular form or arrangement of parts except in so far as such limitations are included in the claims.

What we claim as our invention is:

20 1. An attachment for a ladder comprising a mounting plate adapted to be secured to a part of the ladder, a steadyng member pivotally mounted on said plate, means mounted on said plate engaging three sides of said member for locking said member to said plate in an upwardly projecting position.

25 2. In a ladder attachment, the combination of a mounting plate adapted to be secured to a part of the ladder, a member pivotally mounted on said plate, a clip mounted on said plate and receiving said member between it and said plate when said member is swung to an upwardly projecting position, and a latch pivotally mounted on said plate and lockingly engageable with said clip to hold said member between it, said clip and plate in the upwardly projecting position of said member.

40 ISABELLE J. BACKLIN.
